UNITED STATES PATENT OFFICE.

WILLIAM A. DE LONG, JR., OF PLAINFIELD, NEW JERSEY.

AUXILIARY RIBBON-HOLDER.

1,305,886.

Specification of Letters Patent. Patented June 3, 1919.

Application filed December 26, 1918. Serial No. 268,336.

To all whom it may concern:

Be it known that I, WILLIAM A. De LONG, Jr., a citizen of the United States, and a resident of Plainfield, in the county of Union and State of New Jersey, have invented a new and Improved Auxiliary Ribbon-Holder, of which the following is a full, clear, and exact description.

Among the principal objects which the present invention has in view are: to provide means for readily changing the printing ribbon on typewriters; to multiply the devices for color printing arranged to be readily and quickly substituted for one another; to economize the color inserts of ribbons of the character mentioned; and to provide an attachment so arranged that the ribbon may be readily moved to expose the written or printed character.

20

Drawings.

Figure 1 is a sectional elevation of a holder of the character mentioned constructed and arranged in accordance with the present invention, the same being shown in conjunction with a fragment of a typewriting machine of usual construction;

Fig. 2 is a detail view on an enlarged scale, showing a fragment of a typewriter cylinder having installed thereon a "first" and a "second" sheet of paper and a carbon insert in position to receive printed impressions, an uncolored ribbon being shown in conjunction with the herein disclosed holder;

Fig. 3 is a detail view showing a front view of the holder, and means for installing the same in service;

Fig. 4 is a detail view showing a modified form of the holder wherein may be installed ready for service a series of colored ribbons;

Fig. 5 is a vertical section of the holder, the section being taken on the line 5—5 in Fig. 4;

Fig. 6 is a front view of a modified form of the invention and means for shifting the ribbon in service;

Fig. 7 is a section taken as on the line 7—7 in Fig. 6.

Description.

As seen in the drawings, a standard is provided having a base 10, which is furnished with a channeled bench section 11, the chan-

nel wherein is adapted to hold the lower rail of the lower flange of the frame rail 12 of the typewriter construction.

Erected upon the base 10, is a standard 13. The standard 13 is preferably tubular and is held fixedly to the base 10, by a screw 14, and clamping nut 15 operatively engaging the same. The standard 13 is disposed vertically at the rear of the typewriting machine and approximately in line with the printing station of the type bars 16. The crane-like structure is employed to support one or more harp frames 17. The frames 17 are preferably formed of very light resilient sheet metal bent to form supports 18 at the ends of the hangers 19. Preferably each harp frame 17 is integral with a hanger 19. The hangers 19 are removably attached to the clips 20, which are pendent from the bracket 21 of a resilient suspension yoke 22. The bracket 21 is fixedly attached at 23 to the rail of an elongated slide 24. The free ends of the harp frames 17 are designed to form the tabs 25. Through slits in the tabs 25, extend short sections 26 of colored ink ribbon. The slits are closed to clamp the ribbon between the sides thereof for holding the same in service.

The crane-like structure above referred to has a rod 27. The rod 27 is telescopically mounted on the standard 13. It is secured to a reach bar 28, by means of a pivot 29, and clamp nut 30, which when tightened, draws the engaged members of the rod and bar together, and when loosened permits the pivotal movement of the said bar on the said rod. At the forward end of the said reach bar is secured a slide loop 31. The yoke 22 has sufficient resistance to support the weight of the harp frame 17 and parts connected therewith.

Normally, the harp frames 17 swing outward away from the surface of the paper 32 and the cylinder 33. This provides for the need that the sections 26 shall disengage the paper during the time the same is being shifted or moved.

In Fig. 2 of the drawings, the invention is shown in operative relation to the cylinder 33, having the paper 32, a second sheet 34, and a carbon sheet 35. In some instances, the harp frame 17 may be provided with an uncolored section 26. When so equipped, it will be understood that the harp frame 110

may be dropped into operative position. The section then interposed between the paper 32 and the usual printing ribbon would not print upon the paper while the marking substance of the carbon 35 would be imprinted upon the second sheet 34.

In Fig. 4 of the drawings, a modification of the invention is disclosed. The modification consists principally in that a disk 36 10 is provided which is pivotally mounted by means of a pin 37 on a hanger 38.

When using the modified form employing the disk 36, it will be understood that a number of harp frames, each having a differently colored section 26, is operatively connected with said disk 36 and with the clips 20 carried thereby. When so arranged, it is obvious that the operator of a typewriting machine may rotate the disk 36, so that 20 the harp frame 17 carrying any desired section 26, may be disposed in operative relation to the type printing character and to the printing station of the typewriting machine.

25 When using the apparatus, it is obvious that by shifting the slide 24, different and successive areas of the section 26 may be disposed in the path of the type characters of the type bars 16.

30 The construction shown in Figs. 6 and 7 of the drawings, provides for shifting the section 26 automatically. With this end in view, a rod 41 is pivoted in eyelets 42 to the bar 28. Rigidly connected to the rod 41, 35 is a swing bar 43. At the back of the typewriting machine is an adjustable rod 44, the bent end 45 of which engages the end of the bar 43 and rocks the bar 41 in one direction, while permitting it to pass freely in 40 the opposite direction. The outer end of the bar 41 is bent down to engage the ratchet teeth 46 on the slide 24 shown in Fig. 6. This engagement takes place only when the bar 41 is rocked in one direction.

45 From the foregoing and by reference to Fig. 6 of the drawings, it is obvious that when the carriage and the rod 44 are moved to the right, the bent end 45 of the rod 44 engages the end of the bar 43 and rocks the 50 bar 41 slightly to the right, the bent end of the bar 41 engaging the ratchet teeth 46. A sliding movement is thus imparted to the slide 24 through the loop 31.

It will be seen that as the typewriter carriage returns to the end of the line, the hook 55 passes freely under the end of the bar 43. By this means, it will be seen that the harp frame 17 and section 26 carried thereby, is shifted a predetermined and slight 60 distance at each shift of the carriage of the typewriting machine.

In service, the sections 26 are disposed between the printing ribbon 49 and the sheet of paper 32. When it is desired to discontinue the use of the color sections 26, the

bar 28 is lifted, the harp frame 17 then being elevated out of the path of the type bars 16. While the color sections are in service, they may be momentarily shifted to expose the imprint on the paper. It is for this purpose that the yoke 22 is shaped to allow of the necessary movement of the hanger 19 and parts connected therewith, as well as to provide for lateral resiliency in placing insert 26 in operative position. 75

Claims.

1. An apparatus as characterized comprising a short section of color-filled material; a frame operatively connected therewith; and means for manipulating said frame to place said color-filled material in the path of the printing character of the usual typewriting machine and the paper being imprinted thereby, said means embodying a crane-like structure having a reach bar pivotally mounted at the rear of said machine and supporting said frame at the forward end thereof in superposed relation to the printing point of the type bars of said machine. 90

2. An apparatus as characterized comprising a short section of color-filled material; a frame operatively connected therewith; and means for manipulating said frame to place said color-filled material in the path of the printing character of the usual typewriting machine and the paper being imprinted thereby, said means embodying an overhead suspension frame adapted to swing 100 to and from the operative position, and a flexible member connecting said frames for allowing the color-filled material to be shifted for exposing the imprint made thereby on said paper. 105

3. An apparatus as characterized comprising a short section of color-filled material; a frame operatively connected therewith; means for manipulating said frame to place said color-filled material in the path of the printing characters of the usual typewriting machine and the paper being imprinted thereby, said means embodying a crane-like structure having a reach bar pivotally mounted at the rear of said machine and supporting said frame at the forward end thereof in superposed relation to the printing point of the type bars of said machine; and means for shifting said frame and color-filled material carried thereby. 110

4. An apparatus as characterized comprising a plurality of color-filled members; means for arranging said members circumferentially and in mutually fixed relation; and means for suspending said members normally out of operative relation to the printing point of a typewriting machine, and adapted to be moved successively into operative relation to the printing point of said typewriting machine. 125

1,805,886

5. An apparatus as characterized comprising a plurality of color-filled members; means for arranging said members circularly and in mutually fixed relation; and means for suspending said members normally out of operative relation to the printing point of a typewriting machine, and adapted to be moved successively into opera-

tive relation to the printing point of said typewriting machine, said means embodying 10 a suspension frame, and a disk rotatably mounted on said frame, said disk having means for holding radially thereon, the color-filled members referred to.

WILLIAM A. DE LONG, JR.
